MULTIPLE NEEDLE TUFTING MACHINE

Lyman Hamrick, Gaffney, S. C.

Application July 20, 1944, Serial No. 545,759

1 Claim. (Cl. 112—79)

1

This invention relates to a multiple needle tufting machine having sufficient needles, loopers, and cutters to finish a wide piece of cloth so that this cloth can be cut into shorter lengths for bedspreads.

It is an object of this invention to provide a multiple needle tufting machine having a vertically reciprocable needle bar having sufficient needles therein to cover the width of a bedspread and having a throat plate on which the cloth rests to be pierced by the needles and having mounted for oscillation therebelow a rod having thereon a plurality of loopers and having also mounted for oscillation in timed relation to the oscillation of the looper rod a cutter rod which is adapted upon backward movement of the loopers to sever some of the loops on the loopers together with means for pulling the cloth through the machine in timed relation to the movement of the needles and having a support for supporting a roll of cloth which is unwound and passed through the machine so that a continuous length of bedspread material can be tufted and whereby the continuous length can later be severed into the shorter lengths for complete bedspreads, said machine having a cloth guiding apparatus disposed in front of the needles with means for moving the cloth guiding apparatus laterally of the needles back and forth in any desired pattern to thereby cause the needles to form a circuitous or serpentine row of tufts as the material is passed through the machine.

Some of the objects of the invention having been stated, other objects will appear as the description proceeds, when taken in connection with the accompanying drawings, in which:

Figure 1 is a front elevation of the machine with some of the central portions thereof being broken away;

Figure 2 is a view similar to Figure 1, but showing the cloth feeding apparatus and the support for the cloth roll omitted;

Figure 3 is a rear view of the machine with the central portion thereof being broken away;

Figure 4 is an end elevation of the machine looking from the left-hand end in Figure 1;

Figure 5 is an end elevation of the machine with the upper central portion thereof being broken away, and looking at the right-hand end of Figure 1;

Figure 6 is a vertical-sectional view taken along the line 6—6 in Figure 1;

Figure 7 is a vertical-sectional view taken through the bedplate and the looper and cutter

2

shafts and associated mechanism, and showing the same in forward position;

Figure 8 is a view similar to Figure 7, but showing the parts in a backward position where some of the loops formed on the looper are being cut;

Figure 9 is a top plan view of a portion of the needle bar;

Figure 10 is a front elevation of a portion of the needle bar;

Figure 11 is a rear elevation of a portion of the looper and cutter shaft and associated mechanism;

Figure 12 is a top plan view of the means for moving the cloth guiding means backward and forward and taken substantially along the line 12—12 in Figure 1;

Figure 13 is a top plan view taken from substantially along the line 13—13 in Figure 1;

Figure 14 is a longitudinal sectional view of the shaft and associated parts shown in the upper right-hand portion of Figure 12;

Figure 15 is an isometric view of one of the looper elements and its associated supporting shaft;

Figure 16 is a top plan view of one of the looper elements and its associated supporting shaft;

Figure 17 is a vertical sectional view near the ends of the looper and cutter shafts and showing the bearing supports therefor and being taken along line 17—17 in Figure 1 or immediately to the right of part 17;

Figure 18 is an enlarged top plan view of a portion of the bedplate;

Figure 19 is a detail view showing the course of the tufting yarn forming the loop;

Figure 20 is a view similar to Figure 19, but showing the needle in a different position;

Figure 21 is a vertical sectional view along the line 21—21 in Figure 19;

Figure 22 is an elevation of the clutch mechanism for driving the take-up roll, with the annular confining member removed;

Figure 23 is a vertical sectional view along the line 23—23 in Figure 22, and showing the annular member in place;

Figure 24 is a top plan view of a detail of the cutter shaft and associated parts.

Referring more specifically to the drawings, the numerals 10 and 11 indicate upright end frame members at one end of the machine and 12 and 13 indicate the upright frame members at the other end of the machine. These frame members are joined together at their top portions by means 55 of top angle members 14 and 15. The upper ends

of vertical frame members 10 and 11 are connected by an angle member 16 while the upper ends of vertical frame members 12 and 13 are connected together by a similar angle member 17.

Connecting an intermediate portion of the left-hand vertical frame bars 10 and 11 is a cross bar 18 which projects frontwardly and rearwardly from the machine; whereas, vertical frame members 12 and 13 have a similar bar 19. Secured at its ends to the proximate faces of end frame members 10 and 11, 12 and 13 is a bed plate 20 which is in the form of an inverted channel member.

The bed plate 20 has a plurality of elongated slots 22 through which the needles pass in their downward and upward movements, these slots being disposed immediately above the loopers which will be later described. These slots are elongated so as to permit the tufts to ride outwardly through the rear end of the slots and also due to the thickness of the bed plate, they permit the oscillation of the loopers in the slots.

The upper horizontal frame members 14 and 15, in addition to the end angle members 16 and 17 have a plurality of cross angles 23 secured therebetween, the end angles and the cross angle members supporting a plurality of bearings 24 in which is rotatably mounted a main drive shaft 25. This main drive shaft has fixed thereon a sprocket wheel 26 which has mounted thereon a sprocket chain 27 which is also mounted on a sprocket wheel 28 fixed on motor shaft 29 of electric motor 30 which is mounted on a suitable motor support plate 31 which is supported by a plurality of bolts 32 rising upwardly from I-beams 34 secured on top of horizontal top angle members 14 and 15.

Secured on the front angle member 14 is an elongated angle bar 35 having a plurality of holes 36 therethrough through which strands of yarn are adapted to be passed on their way to the needles. Immediately below the angle iron 35 are disposed suitable tension devices 37 through which the yarn is passed, there being a tension device 37 for each strand of yarn. The cross angle members 23 can be made rigid enough to be supported entirely from the front and rear top angle irons 14 and 15, but if desired, additional supports 40 can be secured to a channel member 41 welded at each of its ends to the end vertical angle bars 11 and 13. This channel member 41 has mounted thereon a plurality of bearings 42 in which shafts or rods 43 have vertical sliding movement. These rods 43 at their lower end are fixedly secured to a needle bar 44 which has a plurality of needles 45 therein. This needle bar extends entirely across the machine and is of substantial structure so as not to vibrate, and it has a plurality of vertically disposed holes 46 therein in which the needles 45 are adapted to be adjustably secured by means of set screws 47.

Approximately midway between the holes 46 and nearer the front edge of the needle bar than the holes 46 are vertically disposed holes 48 through which the strands of yarn 49 are adapted to pass on their way to the eye of the needle. The channel member 41 has secured thereto a plurality of downwardly projecting strap members 50 to the lower ends of which there is secured a presser bar 52 having a plurality of holes in its horizontal portion through which the needles pass immediately before piercing the piece of fabric 53 which is to have tufts applied thereto.

The main drive shaft 25 has mounted thereon a plurality of eccentrics 54 which are surrounded by an eccentric shaft 55, the lower end of this shaft being pivotally connected as at 56 to the

upper portion of the rods 43. For each eccentric 54, there is a counter balance 57.

Rotatably mounted in suitable bearings 60 on the rear vertical angle members 11 and 13 is a shaft 61 which has fixedly mounted thereon a roughened take-up roll 62 which is covered with a suitable roughened material having projections thereon similar to the covering for sand rolls in a loom.

Loosely mounted on one end of this shaft 61 is a disk 63 having a plurality of slanting slots or notches 64 therein in which rollers 65 are adapted to loosely rest. Fixedly mounted on the shaft 61 is a cup-shaped circular member 58 which has an annular portion adapted to loosely fit over the periphery of the disk 63. An annular member 66 is secured over the outer edge of the peripheral portion of cup-shaped member 58 to confine rollers 65 which loosely rest in the notches 64. Fixedly secured or integral with the cup-shaped member 58 is an arm 68 which is slotted as at 70 and has adjustably mounted therein by means of a bolt 71 the lower end of an eccentric arm 72 whose upper end surrounds an eccentric 73 fixedly mounted on the main drive shaft 25. The above-described arrangement is similar to the free wheeling feature employed in free wheeling in automobiles. Upon the downward movement of arm 68, the rollers 65 will ride into the narrow portion between the notches 64 and the peripheral portion of the member 58 to move the take-up roll 62; whereas, upon the upward movement of the arm 68, no movement will be imparted to the take-up roll 62. The other end of the shaft 61 has a similar structure to that just described, except that the notches are cut in the opposite direction and like reference characters will apply with the prime notation added and it will there be noted that the arm 68' is fixedly secured to an angle bracket 75 secured on the rear vertical angle member 13. This will hold the shaft 61 in the advanced position and prevent reverse movement of the same. If desired, the arrangement on the left-hand end of the shaft in Figure 3 could be an ordinary friction clutch or brake to hold the shaft 61 in the position to which it is moved by the step by step movement as a result of oscillation of arm 68.

Mounted on the rear vertical angle members 11 and 13 is a pair of brackets 76 which have pivotally connected thereto the upper ends of bars 77, the lower end of the bars 77 having rotatably mounted therein a roller 78 which is adapted to press by gravity against the take-up roll 62 to press the cloth thereagainst the same so that the cloth after being operated on by the needles will pass upwardly between the rollers 62 and 78 and fall downwardly from the top portion of roller 78 onto the floor or a suitable container disposed therebelow.

Extending across the front of the machine and slidably mounted in bearings 79 is a rod 80 which is loosely connected to a crank arm 81 extending from a switch box 82 from which a wire 83 leads to the electric motor 30. Current is brought in through a cable 84 into a control box 85 and a set of wires 86 leads from the control box 85 to the switch box 82, so that by sliding the rod 80, the operator can stop and start the machine at will from any point in front of the machine.

To the proximate faces of the forwardly projecting portions of the angle members 18 and 19 are secured the ends of shafts 92 and 93. Adapted to slide on the upper surface of these shafts 92 and 93 are a pair of cross members 94 and 95.

On the outer ends of these cross members is mounted a squared bar 96 which has an angle member 97 thereon, the exterior surface of which is serrated or roughened so as to prevent the cloth or fabric 53 from slipping while on the surface of angle member 97. The members 94 and 95 are loosely confined on the rods 92 and 93 by means of members 87 spaced from members 94 and 95 by a spacer 88 and bolts 89. Rotatably mounted on top of the inner ends of angle members 94 and 95 is a roller 98 under which the cloth 53 passes on its way to the needles. The front edge of the bedplate channel member 20 has a downturned lip 99 welded thereto and over which the cloth passes. Secured to the angle members 94 and 95 and projecting downwardly is a pair of supports 100 and 101, the lower ends of which are hooked to provide a support for a shaft 102 on which a roll of cloth 53 is adapted to be mounted.

The shaft 102 has collars 103 thereon which may be adjusted to any desired position to hold the roll of cloth in proper alignment with the needles. The cloth table which has been described for sliding movement back and forth on the rods 92 and 93 has a link 106 pivotally secured thereto as at 107 and the other end is pivotally secured on a pin 108 fixed on the upper side of a worm gear 109 which is mounted for rotation on a bracket 110 and meshing with this worm gear 109 is a worm 111 fixed on a shaft 112 rotatably mounted at its ends in bearings disposed on bracket 110.

The shaft 112 has a shoulder 113 and also a shoulder 114 and on the portion 115 of the shaft is loosely mounted a member having V-pulleys 116 and 117 integral with each other and mounted for rotation on portion 115 of the shaft 112. This member 116 is loosely confined on portion 115 by means of a nut 118. The member having V-pulleys 116 and 117 integral therewith has a serrated face 120 projecting to the left in Figures 1, 12, and 14.

There is a key-way 121 mounted in shaft 112, and a clutch member 122 having a serrated face 123 is mounted for sliding movement on the key-way 121. This member 122 has a peripheral groove 125 which is adapted to be engaged by the forked prongs 126 and 127 of a member 128 which is pivotally mounted as at 129 in a sliding block 130 mounted in a suitable guide way, not shown, on the upper surface of a bracket 131, which has an upturned end 132 for confining a compression spring 133, which normally presses the lower end of member 128 to the left in Figure 1.

Rotatably mounted at its ends in a bracket 135 is a shaft 136 having a worm 137 fixed thereon which meshes with a worm gear 138 mounted for rotation in brackets 139 and 140. Worm gear 138 has a plurality of holes 141 into which one or more pins 142 can be inserted for swinging lever 128 on its pivot 129 when the worm gear 138 moves to a position to where a pin 142 will engage the lever 128. The shaft 136 has a V-pulley 143 fixed thereon and a belt 144 extends from pulley 143 to pulley 117. A belt 145 also extends from pulley 116 to a pulley 146 fixedly mounted on main drive shaft 25. Main drive shaft 25 has a hand wheel 147 fixed thereon so that the machine can be turned by hand when desired for its few strokes and adjustment purposes, and the like. The above-described arrangement permits the cloth to be moved back and forth laterally to produce sinuous rows of tufts according to any

desired pattern, depending on the number of pins 142 and their position on worm gear 138.

The main drive shaft 25 has fixed on the left-hand end thereof when viewed from the front of the machine a sprocket wheel 150 on which is mounted a sprocket chain 151 which extends downwardly and is mounted on a sprocket wheel 152 fixed on lower drive shaft 153 which is mounted in bearings 154 and 155 mounted on cross angle irons 156 and 157.

Fixed on this shaft 153 is an eccentric 160 around which is mounted an eccentric arm and hub 161 whose outer end has a bolt 162 therein which is adjustably mounted in a slot 163 in the lower end of arm 164 whose upper end is secured to an oscillating shaft 165. The oscillating shaft 165 is rotatably mounted in suitable bearings 166 secured in cross bars 167 whose ends are vertically slotted as at 168 and are secured for vertical adjustment by means of bolts 169 and 170, which project from blocks 171 and 172 which are fixed to outer surfaces of the vertical side portions of the channel bedplate member 20.

Projecting upwardly from shaft 165 are arms 173 which have rigidly attached to the upper ends thereof a looper holding shaft 174. This looper holding shaft has adjustably mounted thereon a plurality of looper supporting members 175 which members 175 are adapted to be adjusted along the shafts 174 and in proper angularity by means of being split at one end and having a bolt 176 for pressing the two parts together to clampingly engage the shaft 174.

Each member 175 has a rearwardly projecting portion which has a pair of grooves cut vertically from the rear outer corners thereof providing a rib 180, and mounted for vertical adjustment on this rib is a looper supporting member 181 which is forked at its lower end and is adapted to fit on both sides of the rib 180 and the rib 180 has a screw threaded hole therein in which a screw 182 is threadably mounted after being passed through a washer 183 to firmly affix the looper supporting member 181 in vertically adjusted position.

The looper supporting member 181 has secured thereto by means of a couple of screws 184 a looper bill 185 which has a downturned lip 186 at its front end.

Projecting downwardly from oscillating shaft 165 is an arm 187 which has pivotally secured thereto as at 188 a link 189 whose other end is secured by a bolt 190 in any one of a plurality of holes 191 in an arm 192 affixed to and projecting downwardly from oscillating cutter shaft 193. This cutter shaft 193 is rotatably mounted in the vertically adjustable bearings 194 which are slotted at their lower end as at 195 and secured to bars 167 by means of bolt 196 for vertical adjustment on the cross bars 167.

The shaft 193 has fixedly secured thereto and in spaced relation thereto a square bar 197 by means of screws 198 and spacer washers 199 holding the bar 197 in spaced relation to the shaft 193. The bar 197 has adjustably mounted therein short rods 200 which have one end pressing against a flat portion 201 on shaft 193 and are held in adjusted position by means of a set screw 203 and the outer end of each of the short shafts or bars 200 has a vertically disposed slot 204 therein in which a leaf spring like cutter blade such as a piece of hack saw blade 205 is adapted to be adjustably secured by means of a set screw 206 threadably mounted in the end of each of the short bars or rods 200 and en-

gaging the edge of the cutter blade 205 to hold it in adjusted position. The upper end of the cutter blade 205 is beveled into a cutting edge as at 207 and the upper side surface of the cutter blade is adapted to slidably engage the vertical shank portion of the looper 185 at all times as it is flexed by the angular setting of the rods 200 so as to slidably and resiliently engage the side of the looper shank 185 at all times.

In Figure 7, the looper bill 185 is shown in advanced position passing between the yarn and the needle and in such position due to the co-action between the arms 187 and 192 and links 189, the cutting upper end or cutting edge of the blade 205 is in lowered position to allow the loops to move backwardly onto the looper bill; whereas, as the looper moves backwardly, the cutter 205 moves upwardly to the position shown in Figures 8 and 20 to cut the rearwardly disposed loops on the looper bill but leaving one or two uncut loops on the looper bill so as to prevent the yarn from being withdrawn from the fabric on account of the amount of resistance offered to the loops by being in the fabric. Upon rearward movement of the looper bill, the downwardly projecting lip 186 retains the uncut loops on the looper bill and upon each forward movement of the looper bill to form a new loop, the already formed loops on the looper bill are moved rearwardly by the oncoming and newly formed loops to a position where they will be engaged by the cutting edge of the cutter blade to sever the rearmost loops on the looper bill.

Although in several of the views, the presser bar 52 is shown elevated from the fabric for the sake of clearness, it is to be understood that this presser bar 52 in operation has its lower surface in rather close proximity to the upper surface of the fabric.

In Figure 6, there is shown a rod 210 which extends between the front posts 10 and 12 for guiding the yarn on its way from the tension devices 37 to the needle bar 44. This rod is omitted in many of the other views for sake of clearness.

The eccentric 73 is so positioned on the shaft 25 that downward movement of lever 68 will occur to drive the take up roll 62 while the needles are moving upwardly out of the fabric and descending towards the fabric, so that a new portion of fabric will be presented for the succeeding loop to be formed.

Method of operation

Power is delivered from electric motor 30 to the main shaft 25, which by reason of eccentric means, causes vertical reciprocation of the needle bar 44 to cause the needles to penetrate the fabric. Shaft 165 is oscillated by an eccentric arrangement on driven shaft 153. Shaft 165 by

means of arm 187, link 189, and arm 192, oscillates cutter shaft 193.

By referring to Figure 7, it is seen that when shaft 165 oscillates in a counterclockwise manner to move the loopers 185 forwardly, this causes shaft 193 to oscillate in a counterclockwise manner to lower the cutting knives 205 to allow the loops to move backwardly on the loopers. When the needles have reached their uppermost position, the shaft 165 oscillates in a clockwise manner and shaft 193 operates in a clockwise manner to raise the knives 205 upwardly to cut all but the first one or two loops on the looper.

The eccentric 73 on shaft 25 oscillates arm 68, which, by means of overriding clutch 66 gives a step-by-step movement to the feed roll 62 to advance the fabric while the needles are in raised position. By means of belt 145, pulley 116 is rotated which by means of belt 144 rotates shaft 136 which rotates pattern wheel 138 which by means of lever 128 clutches pulley 116 with clutch portion 122 to drive shaft 112 and wheel and gear 109 oscillate the cloth carriage comprising roughened angle member 97 to thus move the cloth back and forth laterally to form sinuous rows of tufts in the fabric.

In the drawings and specification, there has been set forth a preferred embodiment of the invention, and although specific terms are employed, they are used in a generic and descriptive sense only, and not for purposes of limitation, the scope of the invention being defined in the claims.

I claim:

35. In a tufting machine having a plurality of needles for penetrating a fabric and having a looper associated with each needle, means for operating all of the loopers in unison to engage a loop when a needle penetrates below the fabric being passed through the machine, a cutter associated with each looper, and separately mounted therefrom, for engaging the looper at all times and for severing some of the loops on the looper as the looper swings rearwardly when the needles rise upwardly, a feed roll for pulling the fabric through the machine, means driven by the machine for driving the feed roll in timed relation to the reciprocation of the needles, a work support table for supporting the fabric in front of the needles, means for moving the work support table laterally back and forth relative to the needles to thereby form sinuous lines of tufts on the fabric by changing the position of the fabric as it advances to the needles, and pattern means for controlling movement of the work support table including a pattern wheel having pins thereon, and a lever engageable by the pins for rendering active the means for moving the work support.

LYMAN HAMRICK.
